UNITED STATES PATENT OFFICE

2,612,216

CONTINUOUS FLOW MULTIPLE TANK FUEL SYSTEM

David Samiran, Fort Wayne, Ind.

Original application August 1, 1945, Serial No. 608,348, now Patent No. 2,516,150, dated July 25, 1950. Divided and this application December 23, 1949, Serial No. 134,794

3 Claims. (Cl. 158—36.5)

(Granted under the act of March 3, 1883, as amended April 30, 1928; 370 O. G. 757)

1

The invention described herein may be manufactured and used by or for the United States Government for governmental purposes without payment to me of any royalty thereon.

This invention relates to an aircraft fuel system and is a division of my copending application Serial No. 608,348, filed August 1, 1945, and now matured into Patent No. 2,516,150 of July 25, 1950.

In modern aircraft, particularly in warcraft, it is current practice to carry the fuel in a series of separate tanks distributed as uniformly as practicable throughout the available space in the craft, this practice being conducive to uniform weight distribution as well as having the advantage that if one tank is punctured and loses its fuel, the loss will be proportionally less as the number of tanks is greater.

In multiple tank fuel systems as heretofore constructed and arranged, a selector cock has usually been provided with a position for each tank whereby the pilot upon noting that one tank is empty switches the selector to another. This arrangement, however, has the disadvantage that an emergency pump is required which will pump fuel from some assured source while the change-over from one tank to another is being effected, together with a pressure drop sensitive instrument which will start and stop the emergency pump as the pressure situation requires.

The object of the present invention is to provide a multiple tank fuel system comprising a main tank having an electric pump by which fuel may be pumped directly to the suction side of the engine pump, and a series of pressurized tanks with means to direct the fuel forced by pressure from the pressurized tanks into the main tank, with automatically selective means to empty the fuel of the pressurized tanks into the main tank in a predetermined sequence.

Other objects, advantages, and meritorious features will become apparent as the invention is further described with reference to the drawings, wherein:

Fig. 1 is a schematic layout of the improved fuel system which is the subject of this invention; and

Fig. 2 is a schematic layout of a fuel system similar to Fig. 1 but including a pair of auxiliary tanks equipped with spring loaded outlet valves.

Like reference characters refer to like parts throughout the several views.

Referring now to Fig. 1 of the drawings, an

2

aircraft engine 10 carries the usual engine pump 12 which is operatively connected to the engine to be driven thereby and adapted to supply fuel under pressure to the carburetor 14 or to a like fuel metering device. A main tank 16 and two auxiliary tanks 18 and 20 are provided and are normally so connected that the fuel in all of the tanks flows through the main tank 16 to the suction side of the engine pump 12.

10. An electric motor driven pump 22 is arranged to pump from the bottom of the main tank 16, through a pipe 24, selector 26 and pipe 28 to the engine pump 12. The selector 26 is shown in a position which connects the pipe 24 to the pipe 15 28, but is rotatable to a position which connects the pipe 28 to the pipe 48. When the pointer knob 25 points to the indicium M as shown in Fig. 1, the tank 16 is connected directly to the suction side of the engine pump 12, and when 20 the pointer knob 25 is turned ninety degrees anticlockwise to the indicium A, the auxiliary tanks 18 and 20 will be connected to the suction side of the engine pump.

The pressure inlets 38 and 40 at the tops of 25 the pressurized tanks 18 and 20, respectively, are connected to a pressure source 30 by pipes 32, 34 and 36.

30. The fuel discharge openings 42 and 44 are connected by piping 46 and 48 to the top of the main tank 16 and to the selector 26 respectively. A spring loaded valve 50 at the outlet 42 of the tank 18 consists of a seat 52 and a valve head 54 adapted to be pressed upon the seat by a spring 56, whereby, with the same pressure applied at the pressure inlet 38 as at the pressure inlet 40, the fuel in the tank 20 will be delivered to the top of the main tank 16 before the fuel in the tank 18.

40. A check valve 58 in the pipe 46 is biased to prevent return flow to the auxiliary tanks. A float valve 60 hinged at 62 within the tank 16 prevents the pressure source 30 from forcing fuel from the auxiliary tanks 18 and 20 into the main tank 16 faster than it is being pumped out by the electric pump 22. Float valves 64 in the bottoms of the tanks 18 and 20 are arranged to close the fuel outlets 42 and 44 where their respective tanks are empty.

45. The operation of the device herein disclosed and which embodies my invention operates substantially as follows:

50. With all tanks full as shown in Fig. 1, the selector may be turned to the position shown, i. e., with the pointer knob 25 pointing to M and the

engine 10 and the electric motor driven pump 22 started. As fuel is pumped out of the tank 16 by the electric motor driven pump 22, the float 60 drops and allows the pressure source 30 to force fuel from the tank 20, through pipes 46 into the main tank 16 to replace that used. No fuel will flow from the tank 18 because of the spring loaded valve 50 until all fuel has been forced out of the tank 20 whereupon the float valve 64 in the tank 20 will close to prevent air 10 under pressure flowing from the tank 20 to the top of the main tank 16.

As soon, however, as the float valve 64 closes the outlet 44 of the tank 20, the valve 50 will open and fuel will be forced from the tank 18 into the main tank 16 until the tank 18 is empty and its float valve 64 closes the fuel outlet. Fuel will now be supplied to the carburetor 14 by the main tank 16 until that is empty.

The operation just described assumes that there has been no combat damage to the system. However, should the main tank 16 be damaged or the pressurizing unit 30 fails to function, or if for any other reason it became desirable to use the fuel in the auxiliary tanks first, the selector may be turned to the position A and the fuel may be drawn by the engine pump 12 directly from the auxiliary tanks 18 and 20.

In Fig. 1 there is shown a fuel system having only two auxiliary fuel tanks. However it is obvious that one or more auxiliary fuel tanks may be added and the fuel may be fed from them in any desired sequence by providing all but the first auxiliary tank with spring loaded outlet valves of graduated loading so that transfer of fuel therefrom into the main tank 16 will take place in inverse order of the strength of the spring loading of the check valves associated with the respective auxiliary fuel tanks. Such a fuel system is shown schematically in Fig. 2, the system being like that of Fig. 1 except for the addition of another auxiliary fuel tank 118'. In Fig. 2 the system includes a main fuel tank 116 connected to the auxiliary fuel tanks 118, 118' and 120 by pipes 146. The auxiliary fuel tanks are connected to a pressurizing source 130 by pipes 132, 132', 134 and 136. The outlets 142 and 142' of the auxiliary tanks 118 and 118' are provided with spring loaded valves 150 and 150' having a construction like that of valve 50 in Fig. 1. However one valve, such as 150, has a stronger spring loading than the other valve, such as 150'. Therefore after fuel is forced from auxiliary tank 120 by way of outlet 144 and after this tank is emptied, then fuel is fed automatically from auxiliary tank 118' by way of outlet 142' and spring loaded valve 150'. After tank 118' is emptied, then fuel is fed from auxiliary tank 118 by way of outlet 142 and spring loaded valve 150. Thus it will be seen that pressure applied on the fuel in the auxiliary tanks causes transfer of fuel from the auxiliary tank 120 to the main tank 116 before subsequent transfer of fuel from the other auxiliary tanks 118' and 118 to the main tank, with the subsequent fuel transfer taking place from these other auxiliary tanks in inverse order of the strength of the spring loading of the spring loaded valves 150 and 150' associated with the respective auxiliary tanks 118 and 118'.

Having described my invention, I claim:

1. In an aircraft fuel system, a main fuel tank, two auxiliary fuel tanks, an outflow pipe for each auxiliary fuel tank extending from the bottoms of said auxiliary fuel tanks to the outside of said

auxiliary fuel tanks, conduit means flow-connecting the outer ends of said outflow pipes to the top of said main fuel tank, a float valve near the top of said main fuel tank operable to close and prevent fuel inflow through said conduit means into the main fuel tank when the fuel in the main fuel tank rises above a predetermined level and operable to open and permit fuel inflow through said conduit means into the main fuel tank when the fuel in the main fuel tank falls below said predetermined level, a float valve in the bottom of each auxiliary fuel tank to prevent outflow of air through the respective outflow pipes when the auxiliary fuel tanks are empty of fuel, means for applying equal air pressure to the top surfaces of the fuel in the two auxiliary fuel tanks for transferring fuel from the auxiliary fuel tanks into the main fuel tank by way of the outflow pipes and the conduit means, and a spring-loaded check valve in the outflow pipe of one of the auxiliary fuel tanks, whereby said air pressure causes transfer of fuel from the other auxiliary fuel tank to the main fuel tank before the subsequent transfer of fuel from said one auxiliary fuel tank to the main fuel tank.

2. In an aircraft fuel system, a main fuel tank, a plurality of auxiliary fuel tanks, an outflow pipe extending from a point near the bottom of each of the auxiliary fuel tanks upwardly to the outside of said auxiliary fuel tanks, conduit means flow-connecting the outer ends of said outflow pipes to the top of said main fuel tank, valve means for controlling fuel inflow through said conduit means into said main fuel tank and operable to close when the fuel in the main fuel tank rises above a predetermined level and operable to open when the fuel in the main fuel tank falls below said predetermined level, valve means in each auxiliary fuel tank operable to close and prevent outflow of air through the respective outflow pipes when the auxiliary fuel tanks are empty of fuel, means for applying equal air pressure to the top surfaces of the fuel in the several auxiliary fuel tanks for transferring fuel from the auxiliary fuel tanks into the main fuel tank by way of the outflow pipes and the conduit means, and a check valve in the outflow pipe extending from all but one of the auxiliary fuel tanks, whereby said air pressure causes transfer of fuel from said one auxiliary fuel tank to the main fuel tank before the subsequent transfer of fuel from the other auxiliary fuel tanks to the main fuel tank.

3. In an aircraft fuel system, a main fuel tank, a plurality of auxiliary fuel tanks, an outflow pipe extending from a point near the bottom of each of the auxiliary fuel tanks upwardly to the outside of said auxiliary fuel tanks, conduit means flow-connecting the outer ends of said outflow pipes to the top of said main fuel tank, valve means for controlling fuel inflow through said conduit means into said main fuel tank and operable to close when the fuel in the main fuel tank rises above a predetermined level and operable to open when the fuel in the main fuel tank falls below said predetermined level, valve means in each auxiliary fuel tank operable to close and prevent outflow of air through the respective outflow pipes when the auxiliary fuel tanks are empty of fuel, means for applying equal air pressure to the top surfaces of the fuel in the several auxiliary fuel tanks for transferring fuel from the auxiliary fuel tanks into the main fuel tank by way of the outflow pipes and

the conduit means, and spring-loaded check valves in the outflow pipes extending from all but one of the auxiliary fuel tanks and having progressively increasing spring loading throughout the several check valves, whereby said air pressure causes transfer of fuel from said one auxiliary fuel tank to the main fuel tank before the subsequent transfer of fuel from the other auxiliary fuel tanks to the main fuel tank with said subsequent transfer taking place from the other auxiliary fuel tanks in inverse order of the strength of the spring loading of the check valves associated with the respective auxiliary fuel tanks.
